UNITED STATES PATENT OFFICE

JAMES E. TRAINER AND IVAR L. LANGVAND, OF BARBERTON, OHIO, ASSIGNORS TO THE BABCOCK & WILCOX COMPANY, OF BAYONNE, NEW JERSEY, A CORPORATION OF NEW JERSEY

ECONOMIZER

Application filed January 11, 1928. Serial No. 245,970.

This invention relates to an economizer in which the ends of the tubes are connected by return bends in such a manner that the joints are outside of the economizer walls and will be understood from the description in connection with the accompanying drawings in which Fig. 1 is a vertical section through an illustrative embodiment of the invention; Fig. 2 is a section along the line 2—2 of Fig. 1; Fig. 3 is a section similar to Fig. 1 showing a modification; Fig. 4 is an end view showing one of the details; Fig. 5 is an enlarged sectional view showing supports for the tubes; Fig. 6 is a side view corresponding to Fig. 5; Fig. 7 is an enlarged view showing tubes passing through the wall of the economizer; Fig. 8 is an enlarged view partly broken away showing some of the details; and Fig. 9 is an end view corresponding to Fig. 8.

In the drawings, reference character 1 indicates rows of tubes, the ends of which are upset, as shown at 2 in Fig. 8 to thicken the walls at the ends without substantial change of internal diameter. The end walls 3 of the economizer are provided with holes through which the tubes 1 extend. A row of holes 4 is provided near the middle of each side wall of the economizer through which holes the ends of supports 5 for the tubes 1 extend. A casing 6 is spaced a short distance from the walls of the economizer and return bends 8 and 9 are located inside the casing and outside of the economizer walls, and connect the ends of each row of tubes to the ends of the next row, the tubes being staggered with respect to each other, as most clearly shown in Fig. 9. Alternate return bends 9 are longer than the others, so that a spanner wrench can be inserted between the return bends and turn the nuts on bolts that attach the return bends to the tubes, as will be more fully described below.

The ends of the return bends 8 and 9 are threaded, as shown at 10 (Fig. 8) and a

flange 11 is threaded on each end of each return bend and may be spot welded thereto. The flanges are countersunk, as shown at 12, to accommodate the ends of the tubes 1. The upset or enlarged ends 2 of the tubes 1 are 50 threaded as shown at 13, and are also provided with flanges 14 corresponding to the flanges 11. Bolts 15 connect the flanges 11 and 14, and gaskets may be placed in the countersunk portion of the flanges 11 between the ends of the tubes 1 and the ends of the return bends 8 and 9.

Return bends 16 and 17, somewhat longer than the bends 8 and 9, connect the lowermost row of tubes 1 to an inlet header 18. 60 The lower ends of the bends 16 and 17 are provided with flanges 19 and bolts 21 that pass through the flanges 19 and screw into the header 18 force the ends of the return bends 16 and 17 into countersinks 21 in the 65 header 18. Return bends similar to the return bends 16 and 17 connect the uppermost row of tubes 1 to the outlet header 22 and the outlet header is connected to the boiler drum by means of the connection 23 in the 70 usual manner.

The end walls 3 are made up of plate sections 25 of metal (Fig. 7) that are provided with bosses 26 corresponding to the tubes 1, the sections being bolted together as indicated at 27. Holes 28 are provided through the bosses 26 sufficiently large for the enlarged upset ends of the tubes to pass through. The holes 28 are countersunk so as to leave shoulders 29. Split metal rings 30 are placed 75 around the tubes 1 in contact with the shoulders 29 on one face. The inside circumferences of the rings 30 contact with the tubes 1 and the outside circumferences of these rings contact with the circular holes 28 of the plate sections 25 and asbestos packing 31 is introduced into the countersunk portion of the hole 28 so that the rings 30 center the tubes 1 and keep them in place, permitting them to move 80 longitudinally due to expansion and contrac- 85 90

tion, while the asbestos packing prevents gas from escaping. In view of the fact that the rings 30 are made of thin steel, the tubes 1 are permitted to pivot on the same as they bend, which would not be possible if they should fit closely in long holes through cast iron.

The supports 5 for the tubes 1 (Figs. 1, 5 and 6) are made up of pairs of strips 32 and 33 (Figs. 5 and 6), side by side that are provided with notches 34 along their upper edges. The notches 34 are somewhat deeper than half the diameter of the tubes 1 and one end of each notch 34 in the strip 32 is left with an overhanging lip 35 and the other ends of the notches 34 in the strip 33 are left with a similar overhanging lip so that when the strips are moved in opposite directions with the tubes 1 in the notches 34, the tubes will be clamped in place. The strips 32 and 33 are provided with transverse rectangular openings 36, one of which has an inward projection 37 along the end thereof, so that when a wedge 38 is driven into the openings 36, the strips 32 and 33 will be moved in opposite directions and clamp the tubes 1. Bolts 39 are provided for retaining the strips 32 and 33 in their clamping position after the wedge 38 has been inserted. The supports 5 near the middle of the tubes 1 cooperate with the return bends to prevent leakage from developing at the joints by flexing of the tubes. The supports 5 can be readily unloosened to permit removal of any injured tube.

35 In the modification shown in Fig. 3, an intermediate header 40 is connected to a row of tubes a few rows of tubes from the top, and is connected by means of the valved pipe 41 to the water space of the boiler drum 42, so that local circulation of water can take place through the upper rows of tubes while the boiler is being started up.

We claim:

1. In an economizer, rows of tubes connected by return bends, said tubes passing through gas tight openings in the walls of said economizer with the outside surfaces of said tubes contacting with the edges of said openings, said tubes being free to move longitudinally with respect to the walls due to expansion and contraction.

2. In an economizer, rows of tubes connected by return bends, said tubes passing through gas tight openings in the walls of said economizer with the outside surfaces of said tubes contacting with the edges of said openings, said tubes being free to move longitudinally with respect to the walls due to expansion and contraction, said return bends being of different lengths.

3. In an economizer, rows of tubes connected by return bends, said tubes passing through gas tight openings in the walls of said economizer and being free to move longitudinally with respect to the walls due to

expansion and contraction, and adjacent return bends being of different lengths.

4. In an economizer, rows of tubes connected by return bends, said tubes passing through gas tight openings in the walls of said economizer with the outside surfaces of said tubes contacting with the edges of said openings, said tubes being free to move longitudinally with respect to the walls due to expansion and contraction, and means near the middle of said tubes to prevent them from vibrating.

5. In an economizer, an upper and a lower header, rows of tubes connected to each other and to said headers by return bends, said tubes passing through gas tight openings in the walls of said economizer with the outside surfaces of said tubes contacting with the edges of said openings, said tubes being free to move with respect to the walls due to expansion and contraction.

6. In an economizer, rows of tubes connected by return bends, said tubes passing through gas tight openings in the walls of said economizer with the outside surfaces of said tubes contacting with the edges of said openings, said tubes being free to move longitudinally with respect to the walls due to expansion and contraction, said return bends being of different lengths, and flanges connected to said return bends.

7. In an economizer, rows of tubes connected by return bends, said tubes passing through gas tight openings in the walls of said economizer with the outside surfaces of said tubes contacting with the edges of said openings, said tubes being free to move longitudinally with respect to the walls due to expansion and contraction, and clamping means near the middle of said tubes to prevent them from vibrating.

8. In an economizer, rows of tubes having upset ends, flanges connected to said ends, and return bends of different lengths carrying flanges adapted to be connected to the flanges on said tubes.

9. In an economizer, rows of tubes having upset ends, flanges connected to said ends, and return bends of different lengths carrying flanges adapted to be connected to the flanges on said tubes, said last named flanges having countersunk portions into which the ends of said tubes extend.

10. In an economizer, rows of tubes connected by return bends, said tubes passing through gas tight openings in the walls of said economizer and thin rings in said openings on which said tubes rest.

11. In an economizer, rows of tubes having upset ends, elongated flanges connected to said ends, return bends of different lengths connecting said tubes, elongated flanges on said return bends, the length of said flanges extending at an angle to the planes of said return bends.

12. In an economizer, tubes having flanges at the ends thereof, return bends connecting said tubes, and elongated flanges on said return bends, the lengths of said last named flanges being at an angle to the planes of the return bends. 70
13. In an economizer, tubes having flanges at the ends thereof, parallel return bends inclined to the length of said economizer, connecting said tubes, and elongated flanges on said return bends, the lengths of said last named flanges being at an angle to the planes of the return bends. 75
14. In an economizer, tubes having flanges at the ends thereof, return bends connecting said tubes, an end of each last named flange projecting into the bend of an adjacent return bend. 80
15. In an economizer, tubes having flanges at the ends thereof, and return bends connecting said tubes, the alternate return bends being longer than the others by an amount at least as great as the approximate diameter of the tubular portion of a bend. 85
16. In an economizer, rows of tubes having ends with thickened walls and substantially uniform internal diameter, flanges connected to said thickened wall ends, flanged return bends outside of the walls of said economizer and means to connect the tube end flanges to the return bend flanges. 90
17. In an economizer, tubes having thickened end walls, flanges attached to said thickened end walls, return bend connectors having substantially the same bore as said tubes, flanges on said return bends, connections between the tube end flanges and the return bend flanges to make tight joints with the bores of the tubes aligned with the bores of the return bends. 95
18. In an economizer, tubes having thickened end walls, flanges attached to said thickened end walls, return bend connectors having substantially the same bore as said tubes, flanges on said return bends, connections between the tube end flanges and the return bend flanges to make tight joints with the bores of the tubes aligned with the bores of the return bends, the ends of said tubes extending into said return bend flanges. 100
19. In an economizer, tubes having thickened end walls, flanges attached to said thickened end walls, return bend connectors having substantially the same bore as said tubes, flanges on said return bends, connections between the tube end flanges and the return bend flanges to make tight joints with the bores of the tubes aligned with the bores of the return bends, said flanges being so located 115 that when they are drawn together they will cause the ends of the tubes to be pressed against the ends of the return bends within the body of one of the flanges. 120
20. In an economizer, rows of tubes, return bends connecting ends of said tubes, said 130
